UNITED STATES PATENT OFFICE.

CHARLES W. ANDERSON, OF BROOKLYN, NEW YORK.

HOISTING MACHINE.

1,426,139.

Specification of Letters Patent. Patented Aug. 15, 1922.

Application filed June 24, 1920. Serial No. 391,405.

To all whom it may concern:

Be it known that I, CHARLES W. ANDERSON, residing at Brooklyn, in the county of Kings and State of New York, have invented certain new and useful Improvements in Hoisting Machines, of which the following is a specification.

This invention relates to a hoisting machine, and an object of the invention is to 10 provide a simple and efficient and compact hoisting mechanism comprising a hoisting drum with its control elements and an explosive engine of standard type associated with and connected for operating the hoisting 15 drum.

In the accompanying drawings which are to be taken as a part of this specification, and in which I have shown merely a preferred form of embodiment of the invention:—

Figure 1 is a side elevational view of a hoisting machine constructed in accordance with this invention, and

Figure 2 is a top plan view of the structure seen in Fig. 1.

Referring to the drawings for describing in detail the structure which is illustrated therein, the reference character L indicates the hoisting drum mechanism, while the reference character G indicates the engine. These two elements are mounted upon a single heavy base or foundation piece H.

The hoisting drum mechanism consists of a drum 1, mounted to rotate freely upon a 35 shaft 2 which is rotatably supported in bearing standards 3. Rigidly mounted upon the shaft 2, at one end of the drum 1, is a large gear wheel 4, the teeth of which stand in constant mesh with the teeth of a gear pinion 5 mounted upon the main shaft 6 of the engine G. The drum 1 is provided with a cone-shaped clutch surface 7 at its end adjacent the gear 4, and the gear 4 is provided with a correspondingly shaped clutch 40 surface 8 with which the surface 7 engages when it is desired to drive the drum by means of the gear, as will be readily understood.

A suitable frame part 34 is provided carrying a screw 14 having an operating handle 20 for controlling this clutch in the usual manner.

The drum 1 is provided with a brake band 40 having one of its ends fixed, as at 41, and 55 having its other end, as 42, connected with a lever 43 mounted upon a shaft 44 carrying

a foot lever 45. Pressure of the operator's foot upon the lever 45 will draw the brake band tight to oppose rotation of the drum. A counter weight 46 is carried by an extension piece 47 of the foot lever 45, projecting beyond the shaft 44, said counter weight being adjustable along the extension 47 for altering its counter-balancing value and being furnished with a set screw 48, or the like, 60 by means of which it may be held in any position of adjustment.

The drum is also provided with a ratchet wheel 49 arranged to be engaged by a pawl 50 to positively hold the drum against rotation in one direction. The pawl 50 may be mounted for operation in any desired manner but preferably is carried by a short shaft 51 which has connected therewith a hand lever 52 projecting to a convenient position 70 to be manipulated by the operator. The lever 52 is preferably weighted, as at 53, and is so disposed that it will stand by gravity in either a gripping or non-gripping position.

Assuming that the engine G is operating, the gear pinion 5 and large gear 4 rotate continuously. The drum 1 may be caused to rotate with the gear 4, or not, according to the will of the operator. To cause rotation 85 of the drum the operator has simply to press down the lever 20 for engaging the clutch 7—8. Lifting of the lever 20 will release the clutch 7—8. Rotation of the drum, while the clutch 7—8 is released, may be controlled 90 by the brake lever 45, it being understood, of course, that rotation of the drum, while the clutch 7—8 is released, is usually a rotation imparted to the drum by the unwinding of rope or cable which was wound upon the drum while the clutch was in engagement, as for instance in the lowering of a load previously lifted.

The pawl 50 may be moved into engagement with the ratchet 49 whenever it is desired to positively hold the load elevated.

It will be seen that thus through the arrangement of foot and hand levers described a single operator may conveniently and efficiently control the operation of the drum at 105 all times.

As above suggested, it is the particular feature of this invention to bring all the elements of the device into compact and efficient relationship with each other and to at 110 the same time enable the use of a standard explosive engine. In this connection it is

to be particularly noted that the foundation member H supports the hoisting mechanism L and the engine G in what might be termed an overlapping position and yet in a position where the full functions of each element are obtained without interference one with the other. For instance, the two counter-balance, or fly wheels, 54—55, at opposite sides of and forming parts of the engine, extend into positions overlapping opposite ends of the drum, the large gear 4 at the same time lapping inside of the counter-balance wheel 54 and correctly and efficiently intermeshing with the pinion 5. The bearings 3, carrying the drum, are formed in standards which conform to the shape and position of the counter-balance wheels 54—55, and the levers 20 and 45 lap back again over the outer surface of the counter-balance wheel 55, a marked economy in space being thus provided. The correct functioning of all the parts of the hoisting mechanism is fully provided for, and the same is true regarding the engine. At the same time the hoisting drum is directly connected with the engine so that the possibility of trouble and annoyance regarding the connections is reduced to a minimum. A high degree of efficiency is also attained. As many changes could be made in this construction without departing from the

scope of the invention as defined in the following claim, it is intended that all matter contained in the above description, or shown in the accompanying drawings, shall be interpreted as illustrative only and not in a limiting sense.

Having thus described my invention, what I claim as new and desire to secure by Letters Patent is:—

The combination with a gas engine of standard type comprising a drive shaft, an explosive cylinder for driving said shaft, a pinion fixed upon said drive shaft, and a pair of fly wheels also fixed upon said drive shaft spaced apart at opposite sides of the engine, of a hoisting drum positioned partly between said fly wheels, a carrying shaft for said drum arranged substantially parallel to said drive shaft, a pair of bearing standards for said carrying shaft, a common base from which said engine and said standards rise, control levers for the drum closely adjacent the engine, and a drive gear for said drum fixed to said carrying shaft being positioned partly between said fly wheels and directly intermeshing with said pinion.

In testimony whereof I affix my signature in the presence of a witness.

CHARLES W. ANDERSON.
